UNITED STATES PATENT OFFICE

RALPH S. TYLER AND HERBERT McGEORGE, OF CLEVELAND HEIGHTS, AND WILLIAM M. REICHART, OF CLEVELAND, OHIO, ASSIGNORS TO THE CHANDLER AND PRICE COMPANY, OF CLEVELAND, OHIO, A CORPORATION OF OHIO

GAUGE LOCK

Application filed October 13, 1927. Serial No. 225,953.

The present invention relates to a locking device for the back gauge of a paper cutting machine or the like, and the principal object thereof is to provide such a locking mechanism which will be positive in its effect and easy to operate and which is very simple in construction and consequently extremely free from disorders.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:—

20 Fig. 1 is a plan view of the table of such a machine; Fig. 2 is a transverse section taken substantially on the line 2—2, of Fig. 1; and Fig. 3 is a further sectional detail.

The reference numeral 1 indicates the bed 25 of the machine which is provided with a longitudinal slot 2 running practically the full length of the bed and provided at its front end with an enlargement 3, as is clearly shown in Fig. 1. A back gauge 4 is provided with a 30 tongue 5 adapted to extend through the slot 2 and to receive on its lower end a lug 6 secured to said tongue by a screw 7. The table 1 is provided with a downwardly projecting rib 8 and adjacent one end of said slot, upon 35 which one side of the lug 6 abuts, while the other side of said lug bears against the under side of a sliding taper gib 9 mounted in a wedge-shaped channel 10 formed on the under side of said bed and opening into said 40 slot 2. The under side of said bed is further provided with an angular rib 11 bounding one side of said channel 10, and a plurality of brackets 12 are attached to said rib 11 and extend under the gib 9 to hold said gib 45 securely in said channel.

The gib 9 is provided adjacent its forward or larger end with a reduced extension 13 provided on its free edge with rack teeth 14. Pivotaly mounted at 15 on the under 50 side of the bed is a lever 16, one end 17 of

which is provided with a segmental pinion 17 having teeth in mesh with the rack teeth 14, and the other end 18 of which is pivotally connected as at 19 with a link 20. The other end of said link 20 is pivotally attached, 55 as at 21, to an arm 22 on a rockshaft 23 attached to said bed, and a handle 24 is also engaged with said rockshaft 23.

Also attached to the under side of the bed 1 and adjacent the slot 2 are pulleys 25 and 60 26 at the front and rear end of said bed, respectively, and a cable 27 is mounted over said pulleys and is attached to the lug 6, as clearly indicated in the drawings. A hand wheel 28 is non-rotatably attached to the 65 pulley 25. It is to be understood that a chain and sprocket arrangement may be substituted for the described cable and pulley arrangement.

In operation the hand wheel 28 is rotated 70 to cause rotation of the pulley 25 which results, through the agency of the cable 27 attached to the lug 6, in a movement of the back gauge 4 longitudinally of the bed 1. When the gauge 4 has been brought to the desired 75 position on the bed 1, the handle 24 is moved about the axis of the rockshaft 23 in a clockwise direction, such movement resulting in a counter-clockwise rotation of the lever 16 about the pivot 15 and a consequent reciprocation toward the left, as viewed in Fig. 1, of the gib 9. Such reciprocation causes the gib 9 to move to the right as viewed in Fig. 1 to jam the tongue 5 between said gib 9 and rib 8, thus preventing movement of the tongue 5 80 and the gauge 4 on the bed. 85

It has been found that in practice the present lock is much more satisfactory than any that has been known before the present invention in that it is more simple and yet more positive than any lock for this purpose which is known to the applicant. It also allows the tongue to be unusually free in the slot when not locked so that the operator can move the back gauge back and forth with slight effort, 90 greatly increasing the productiveness of the machine. On the other hand when the tongue is locked by the taper gib all clearance is taken up so that there is no lost motion such as exists in other types of sliding 95 100

mechanisms and which results in inaccuracy in cutting stock at the ends of the back gauge.

Other modes of applying the principle of my invention may be employed instead of the 5 one explained, change being made as regards the mechanism herein disclosed, provided the means stated by any of the following claims or the equivalent of such state means be employed.

10 We therefore particularly point out and distinctly claim as our invention:—

1. In a work-holding table, a bed, an adjustable back gauge mounted on said bed, means unobstructive of free access to the 15 table for adjusting said gauge, wedge means having a thrust parallel to the plane of the table for locking said gauge in adjusted position, and hand-controls for said adjusting means and said locking means both conveniently adjacent the operator's station.

2. In a work-holding table, a bed, a slot in said bed, a back gauge having a tongue depending therefrom and extending through said slot, means engaging said tongue for adjusting said gauge longitudinally of said bed, and separate means laterally engaging said tongue for locking said gauge in adjusted position.

3. In a work-holding table, a bed, a slot, 30 in said bed, a back gauge having a tongue depending therefrom and extending through said slot, a pulley mounted at each end of said bed on the under surface of said bed, an endless cable mounted on said pulley, and attached to said tongue, a hand wheel connected with one of said pulleys for moving said cable to adjust said back gauge longitudinally of said bed, and wedge means laterally engaging said tongue for locking said gauge 35 in adjusted position.

4. In a work-holding table, a bed, a slot in said bed, a back gauge having a tongue depending therefrom and extending through said slot, means engaging said tongue for adjusting said gauge longitudinally of said bed, a wedge-shaped channel extending longitudinally in the under side of said bed opening into said slot, a wedge-shaped gib mounted in said channel and adapted to engage said tongue, and means engaging said gib, and adapted to reciprocate the same to lock said gauge in adjusted position.

5. In a work-holding table, a bed having a slot therein, a back gauge mounted on said bed and provided with a tongue extending through said slot, means engaging said tongue for adjusting said gauge on said bed, a wedge-shaped channel formed in the underside of said bed and opening into said slot, a wedge-shaped gib mounted in said channel, rack teeth on said gib, a pivot mounted on the underside of said bed adjacent one end of said channel, a segmental pinion on said pin, the teeth thereof engaging said rack teeth, a bell crank lever pivoted

to the under side of said bed adjacent the end thereof, and a link connecting said lever with said pinion.

Signed by us, this 10th day of October, 1927.

RALPH S. TYLER.
HERBERT McGEOERGE.
